UNITED STATES PATENT OFFICE.

JACOB FELBEL, OF NEW YORK, N. Y., ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,026,640

Specification of Letters Patent.

Patented May 14, 1912.

Application filed October 3, 1910. Serial No. 585,119.

To all whom it may concern:

Be it known that I, JACOB FELBEL, a citizen of the United States, and resident of the borough of Manhattan, city of New York, in the county of New York and State of New York, have invented certain new and useful Improvements in Type-Writing Machines, of which the following is a specification.

10 My invention relates to typewriting machines and particularly to the tabulator mechanisms thereof.

The principal object of the invention is to increase the rapidity with which tabulator work can be turned out. I do this by providing a tabulator key of such character that it can be operated by the palm or flat part or body of the hand without removing the fingers from the key-board, which thus 20 requires less attention on the part of the operator than has heretofore been necessary to actuate the tabulator. This key is an auxiliary key or additional to the usual tabulator key and preferably it and its connections are in the nature of a simple attachment which can readily be put on any typewriter and can be removed or omitted as desired.

30 My invention consists in certain features of construction and combinations and arrangements of parts which will be fully set forth herein and particularly pointed out in the claims.

In the accompanying drawings, Figure 1 35 is a side elevation of a typewriting machine having my invention applied thereto, parts of the machine being shown in vertical section. Fig. 2 is a fragmentary top plan view with part of the machine frame in section. Fig. 3 is a rear elevation of part of the tabulator. Fig. 4 is a transverse vertical section showing the manner of securing the attachment to the frame of the typewriter. Figs. 40 5 and 6 are respectively a top plan view, partly in section, and a side elevation, illustrating a modification of the invention.

I have shown my invention as an attachment to the Monarch typewriter. The main frame of said typewriter comprises a base 1 50 having a forward extension that incloses the keyboard, said extension including a side bar 2. The posts 3, top plate 4, standards 5, stationary rails 6, carriage 7, feed rack 8, feed pinion 9 and escapement 10 are all of the ordinary Monarch construction, said

feed rack being as usual capable of being lifted out of mesh with the pinion 9 in order to release the carriage for a free run under the impulse of the spring drum 7^a. The tabulator is also of a well-known construction and comprises a column stop bar 11 mounted on arms 12 projecting from the carriage 7 and having column stops 13 adjustably mounted thereon. These column stops are adapted to be engaged by an "eagle-claw" stop 14 which is pivoted at 15 to a bracket 16 secured to the upper stationary rail 6 about the middle of the machine. This "eagle-claw" or stationary stop is normally held by a spring 17 in the position shown in Fig. 1 where it is out of the path of the column stops 13. The stop 14 is adapted to be moved into the path of the stops 13 by means of a push bar 18 projecting upward from a rack lifter 19, the stem of which is operated in the usual way by a lever 20 pivoted to the underside of the top plate 4. Said lever is operated by a vertical pull link 21 connected at its lower end to a bell crank 22 pivoted to the right-hand rear post 3, and said bell crank is in turn operated by a long push rod 23 extending toward the front of the machine where it carries a push key 24, which heretofore has always been operated directly by the finger 85 of the operator to actuate the tabulator. The key 24 has a hollow interiorly threaded stem 24^a that screws onto the threaded portion of the rod 23 and is held by a check nut 23^a in adjusted position. The rack lifter 19 has ears that lie beneath the feed rack 8 and the construction is such that when the key 24 is pushed toward the rear of the machine, said rack lifter and the push bar 18 are moved upward, lifting the rack out of engagement with the pinion and moving the stop 14 into the path of the stops 13. 90 95

My attachment comprises a frame, clamp or supporting plate 25 which is mounted on the main frame of the machine in such a way that it can be secured to the typewriter without any modification of said frame. In mounting my attachment on the particular machine shown in the drawing, this plate is secured to the right-hand side bar 2 of the forward extension of the typewriter frame. The support or bracket 25 consists of a plate of metal stamped out in the form shown and having at its upper part an ear or projection 26 which is bent around to 100 105 110

conform to the curvature of the upper edge of the bar 2 and hook thereupon. The base 1 of the Monarch machine has an outwardly curved part 27 which constitutes a sort of downward continuation of the post 3 and affords a socket for a rubber foot piece 27^a. The plate 25 is curved as shown to extend around and back of this part 27 of the frame. At its rear end said plate is secured 5 to the base by a screw 28, the particular location of which in the present instance has been determined by the fact that the Monarch machine as manufactured has a screw at that point which constitutes part of the base-board clamping device. A screw 29 is 10 threaded through the plate 25 and is formed with a conical or beveled head as shown in Fig. 4. When this screw is tightened it both 15 clamps the lower edge of the plate 25 firmly 20 against the bar 2 and by reason of the beveled form of the head of the screw, draws 25 the plate 25 downward and the ear or hook 26 down into clamping engagement with the upper edge of the bar 2. It will be seen that 25 this plate can be secured to the framework of the machine in a very short time by means so simple as to require no especial skill.

A substantially horizontally disposed 30 main lever 30 is pivoted at its rear end to the plate 25 at 31. The lever 30 is here shown as made of sheet metal and its forward end is bent or fashioned into a key 32 of a size considerably greater than that of 35 ordinary finger keys. This key 32 lies over the frame bar 2 and has secured to its underside a buffer or cushion 33, of rubber or other suitable material, adapted to strike against the bar 2 when the key is fully depressed. A sub-lever 34, here shown as a 40 bell crank, is pivoted to the plate 25 at 35 and the upper end of said lever is adapted to press against the key 24. The lever 34 has a rearwardly extending arm 36 which is 45 connected with the key lever 30 by a link 37 pivoted to said key lever and to the bell crank. The construction is such that when the key 32 is depressed the upper end of the bell crank 34 pushes the key 24 toward the 50 rear of the machine and operates the tabulator. The bell crank 34 and key lever 30 may be restored to normal position by the restoring spring 17 of the tabulator.

In Figs. 5 and 6 I have shown a modification. In the form shown in the first four figures of the drawings, the auxiliary tabulator key is depressible, and I prefer that it be so. In Figs. 5 and 6 I have, however, shown an upstanding, auxiliary tabulator 60 actuating key adapted to be struck with the outer edge of the right hand and moved laterally. In said figures the plate 42 constitute a support corresponding to the plate 25 of the other form, and said plate 65 42 has a part 43 bent over the top of the

bar 2 as before. The lower edge of said plate 42 is bent under the lower edge of the bar 2, and two binding screws 44 are threaded through the flange thus formed and tightened to hold the plate in place. An ear 45 is formed and bent off from the plate 42 so as to have a flat horizontal top and the main key lever 46 is pivoted to said ear 45 on a screw 47 having a vertical axis and threaded into said ear. The forward 70 end of this lever is bent up to form a handle or key 48 adapted to be swung toward the right by the edge of the body portion of the operator's hand. It will be seen that this can be done without removing 80 the fingers from over the printing keys 49. The lever 46 has an ear or lever arm 50 that lies in front of a vertical sub-lever 51 of the third order, which is pivoted at 52 to the plate 42 and which at its upper end 85 stands in front of the button or key 24. The construction is such that when the key lever 46 is thrown toward the right the ear or lever arm 50 moves toward the rear of the machine and operates the tabulator through the 90 lever 51 and the key 24. The return motion of the parts of the attachment is limited by a stop which is here shown as consisting of a lug 52^a bent up from the ear 45 in position to arrest an arm or lug 53 on the lever 95 46 when the parts reach normal position.

It has been found in practice that a device of this character expedites considerably the execution of work involving the frequent use of the tabulator. For example, 100 some railroad billing work requires wide sheets of paper and on said sheets short items are written in a number of columns. In doing this work the tabulator is in constant demand. With a device on the machine of the character described, the operator can write an item and then with the palm of the hand depress the key 32 or with the edge of the hand strike aside the key 48 without moving the fingers from the 105 printing keyboard. Even while holding the auxiliary tabulator key in its operated position the fingers of the right hand are poised over the printing keys ready for action the instant the carriage is arrested by 110 the tabulator stops. Moreover, this key is in such position and is operated by such a part of the hand that the operator does not have to look at it or to fix his attention on it in order to operate it successfully. The 115 operator's mind is thus not diverted from the matter to be written.

This auxiliary actuating mechanism can be built into the machine if desired but I prefer to make it as an attachment as shown 120 which can be added to existing machines at slight expense and with little trouble. It will also be observed that the auxiliary actuating mechanism is loosely connected to the tabulator mechanism proper and com- 125 130

prises two levers connected together, the main lever bearing the large key to be operated by the palm or hand of the operator, and the other or supplemental lever to more 5 immediately act on the tabulator mechanism proper, said supplemental lever being so connected to said main lever as to cause the supplemental or sub-lever to act in the proper direction to be effective on the tabulator mechanism. The auxiliary actuating 10 mechanism it will also be noted comprises a system of levers, at least two in number, for transmitting the blow of the hand in proper direction and causing the final lever to work 15 to the required extent to operate on the tabulator.

The invention is, of course, adapted or adaptable for use in connection with other styles of typewriting machines, having other 20 sorts of tabulator keys; and it is obviously not essential that the attachment operate directly on the finger key itself.

Various changes in detail construction, arrangement and mounting may be made without departing from the essence of my invention.

What I claim as new and desire to secure by Letters Patent, is:—

1. In a typewriting machine, the combination with a carriage and printing keys, of tabulator mechanism including a built-in tabulator key and a detachable tabulator key, said detachable key having a comparatively large surface and detachably mounted 35 at one side of the key board in position to be operated by the body of the hand without removing the fingers from the key-board.

2. An attachment for a typewriting machine having printing keys and a tabulator mechanism having an operating key, said attachment comprising a frame adapted to be detachably secured to the framework of the typewriting machine, an auxiliary key 40 with a comparatively large surface, and means operated by said key for operating said tabulator key, the said attachment key, when the attachment is in place on the machine, being situated at one side of the printing keyboard in position to be operated by the flat part of the hand without removing the fingers from the keyboard.

3. An attachment for a typewriting machine having a tabulator, a tabulator key 45 and printing keys, said attachment comprising a frame adapted to be attached to the framework of the typewriting machine, a key lever having a key with a comparatively large surface, and means including a second lever mounted in the attachment and operated by said key lever for operating said tabulator key, the attachment key, when the attachment is in place on the machine, being situated at one side of the printing keyboard in position to be operated by the flat

part of the hand without removing the fingers from the keyboard.

4. An attachment for a typewriting machine having a tabulator, a tabulator key and printing keys, said attachment comprising a frame adapted to be attached to one of the side bars of the main frame of the typewriting machine, a key lever pivoted to said detachable frame and having an enlarged key, and means operated by said key 70 lever for operating said tabulator key; the attachment key, when the attachment is in place on the machine, lying over said side bar in position to be operated by the flat part of the hand and to be arrested by said side bar at the end of its down stroke.

5. An attachment for a typewriting machine having printing keys, a tabulator and a push key for said tabulator, said attachment comprising a frame or support adapted to be attached to the frame of said typewriting machine, a horizontal key lever mounted on said support, and an upright lever mounted on said support and operated by said horizontal key lever and adapted to 80 operate said push key.

6. An attachment for a typewriting machine having printing keys and a tabulator, said attachment comprising an approximately horizontal key lever having a broad 90 key for operation by the palm of the hand, a bell crank arranged to operate said tabulator, and a link connecting said bell crank with said key lever.

7. In a typewriting machine, the combination with a carriage, and a tabulating mechanism, of an auxiliary actuating mechanism therefor comprising a system of levers detachably connected to said tabulating mechanism, one of said levers being arranged to 100 actuate another.

8. In a typewriting machine, the combination with a carriage, and a tabulating mechanism having a finger actuated part, of an auxiliary actuating mechanism loosely connected to said finger actuated part and comprising a plurality of actuating levers.

9. In a typewriting machine, the combination with a carriage and a tabulating mechanism having a finger actuated part, of an auxiliary hand actuated mechanism detachably connected to the framework of the typewriter and loosely connected to said finger actuated part, said auxiliary mechanism comprising a plurality of actuating levers, one of which bears a large key or head arranged at the side of the keyboard and over that part of the framework to which the auxiliary mechanism is attached.

10. In a typewriting machine, the combination with a carriage, and a tabulating mechanism having a finger actuated part at the front side of the machine, of an auxiliary hand actuated mechanism loosely connected to said finger actuated part and

mounted upon a side bar of the framework of the machine in the vicinity of the keyboard, said hand actuated mechanism comprising a lever having a large key or head 5 arranged immediately above the said side bar and arranged to be arrested by said side bar and comprising also connections from said lever to said finger actuated part.

11. In a typewriting machine, the combination with a carriage, and a tabulating mechanism having a finger actuated part, of an auxiliary actuating mechanism therefore connected to said finger actuated part and comprising a main hand actuated lever 10 and a sub-lever.

12. In a typewriting machine, the combination with a carriage, and a tabulating mechanism having a finger actuated part, of an auxiliary actuating mechanism comprising a bracket or clamp detachably connected to the side bar of the base frame adjacent the keyboard, and a hand actuated lever having a broad surface for operation by the palm of the hand, and connections 20 from said lever to said finger actuated part of the tabulating mechanism.

13. In a typewriting machine, the combination with a carriage, and tabulating mechanism having a finger actuated part, of an auxiliary actuating mechanism comprising a bracket or clamp attached to the right side bar of the base frame adjacent the keyboard of the machine, and a main hand actuated lever with a large key or 30 head arranged over said side bar, and a sub-lever connected to said key actuated part of the tabulator.

14. In a typewriting machine, the combi-

nation with a keyboard, a tabulating mechanism, and a main tabulator key controlling 45 said mechanism, of an auxiliary tabulator-controlling device comprising a clamp removably mounted on the frame of the machine, an auxiliary key lever pivoted to the clamp, said auxiliary lever having a key, an arm 45 pivotally mounted on the clamp and operatively connected with the auxiliary key lever, and means connected to the arm and arranged to operate the main key and to enable the latter to operate independently of 50 the auxiliary key.

15. In a typewriting machine, the combination with a tabulating mechanism and a main key and key lever to operate the latter, of an auxiliary tabulating key lever removably pivoted to the frame and having a comparatively broad key overhanging the frame.

16. An attachment for keyboard-operated typewriting machines having tabulating mechanism controlled by a main key, comprising an auxiliary tabulating key having a comparatively broad surface, said auxiliary key being removably fastened to the frame of the machine and loosely connected with the main tabulating key to operate the latter, and to enable the latter to be operated independently of the auxiliary key.

Signed at the borough of Manhattan, city of New York, in the county of New York and State of New York this 1st day of October A. D. 1910.

JACOB FELBEL.
